CIGAR LIGHTER AND THE LIKE

Filed July 29, 1924

Fig. 3.

INVENTOR

Charles H. Cuno

ATTORNEY

UNITED STATES PATENT OFFICE.

CHARLES H. CUNO, OF MERIDEN, CONNECTICUT, ASSIGNOR TO THE CUNO ENGINEERING CORPORATION, OF MERIDEN, CONNECTICUT, A CORPORATION OF CONNECTICUT.

CIGAR LIGHTER AND THE LIKE.

Application filed July 29, 1924. Serial No. 728,837.

To all whom it may concern:

Be it known that I, CHARLES H. CUNO, a citizen of the United States of America, residing at Meriden, county of New Haven, 5 State of Connecticut, have invented a new and useful Cigar Lighter and the like, of which the following is a specification.

My invention relates particularly to cigar lighters, trouble lamps, etc., and the construction of the casing and means for supporting it on the instrument board of an automobile or the like.

The main object is to simplify and cheapen the construction and facilitate its 15 installation.

Another object is to mount the cigar lighter or the like in such a manner as to avoid defacing the instrument board.

Another object is to make the construction 20 more compact.

In carrying out the invention the casing for the reel is provided with a projecting shelf or flange adapted to be secured to the lower edge of the instrument board. Details of the preferred form will be understood from the accompanying single sheet drawings and description.

Figure 1 is a perspective view showing parts of the device separated.

Figure 2 is a side view showing the device mounted on the lower edge of a wooden instrument board.

Figure 3, which is a smaller view, shows the device mounted on the lower edge of a metal instrument board or dash.

The casing is preferably made up of sheet metal and may consist of a strip 5 secured to the edges of the opposite side plates 6—6 and a face plate 7. The reel 8 may be of any suitable construction as shown, for instance, in the prior Cuno Patents Nos. 1,208,504, 1,342,015, 1,355,943, 1,378,013, or 1,422,180. The conductor or cable 9 carries at its outer end a holder 10 for a trouble lamp or cigar lighter of any suitable construction.

The parts of the casing may be held together in any suitable manner. In the instance illustrated the edges of the strip 5 are beaded at 11 so as to embrace the edges of the side plates 6 and these heads are provided with perforations through which the lugs 12 extending from the edges of the plates 6 may pass and be bent over to lock the parts together. The sides of the casing

are also held together by the spindle or shaft 13 of the drum or reel. The face plate 7 is preferably provided with flanges 14 which embrace the front edges of the sides 6. The strip 5 is provided with lugs 15 and 16 which are bent over the upper and lower ends of the face plate 7.

The terminals 17 and 18 of the device may conveniently be secured to the part 5 of the casing. Such a device may be provided with any convenient form of cut-out or switching means such as is disclosed in the foregoing patents, or it may be provided with a switch having an operating button 19 so that the circuit is normally open but 70 may be closed by pressure on the button 19.

The lower end of the face plate 7 is provided with a collar 20 secured in place, for instance, by spinning or flanging the inner edge or by a nut at the back of the face 75 plate. Such a construction is usually secured to the back of the instrument board and provided with a tube which projects through the board. This, of course, requires the cutting of a hole in the board and means 80 that the cigar lighter or lamp must project a substantial distance beyond the instrument board. To avoid these objections I provide the face plate 7 with a flange or shelf 22 which projects forwardly and is adapted to 85 be secured directly to the lower edge of the instrument board 23, for instance, by means of one or more screws 24 which pass upwardly through the holes 25. For convenience in manufacture this face plate is 90 formed of two angular parts suitably secured to the body of the casing so that the shelf 22 is of double thickness, and therefore, of maximum stiffness with a minimum amount of metal. The two thicknesses of 95 the shelf may be suitably riveted or welded together or made of a single piece of metal bent back upon itself.

Such a construction can be readily installed by anyone in a very few minutes 100 without disfiguring the instrument board. Furthermore this construction leaves the cigar lighter much less obtrusive than if seated in the outer face of the instrument board where the lighter would necessarily 105 project much further. Obviously the installation would be the same on a metal covered wood instrument board.

In case the instrument board 26 is of metal the cigar lighter may be secured to the 110

lower flange by means of one or more bolts 27.

Obviously such a construction can be readily removed from the instrument board 5 without disfiguring it or leaving any visible opening.

I claim:

1. A construction of the character described comprising a reel casing having a 10 face plate with an opening at one end for the cigar lighter or the like and provided with a projecting flange or shelf adapted to be secured to the under edge of the instrument board of an automobile.

15 2. A construction of the character described comprising a reel casing having a flange or shelf projecting outwardly from its front edge adapted to be secured to the under edge of the instrument board of an automobile and having a cable opening beneath said flange.

25 3. A construction of the character described comprising a reel casing having a face plate with an opening at one end for a cigar lighter or the like and provided with an integral forwardly projecting supporting flange or shelf.

4. A construction of the character described comprising a reel casing having a 30 substantially horizontal supporting shelf projecting forwardly from the front edge and provided with an opening for a vertical supporting screw.

35 5. A construction of the character described comprising a reel casing having a two-part face plate with an opening at one end for the cigar lighter or the like and provided with a double projecting supporting flange or shelf.

40 6. A construction of the character described comprising a reel casing composed of a **D** shaped strip having lugs at its opposite ends and a face plate having its upper and lower ends embraced by said lugs, side plates interlocked with the edges of said strip and the edges of said face plate,

a reel in said casing having a spindle supported in said side plates, said face plate having an outwardly projecting supporting flange intermediate its upper and lower ends, 55 and a cable opening below said flange.

7. A construction of the character described comprising a reel casing composed of a strip having beads on its opposite edges, side plates having lugs projecting through 60 said beads, a face plate having said flanges embracing the front edges of the said plates, the opposite ends of said strip having lugs bent over the upper and lower ends of said face plate, said face plate having an outwardly projecting supporting flange or shelf 65 intermediate the upper and lower ends, and an opening for the conductor cable of a cigar lighter below said flange.

8. A construction of the character described comprising a reel casing, a forwardly projecting supporting flange connected thereto, and an anchorage member extending upwardly through said flange for securing 70 said flange to the lower edge of an instrument board.

9. A construction of the character described comprising a casing having an opening provided with a seat, a reel mounted within said casing, a holder member movably seated in said opening, a cable connecting said reel and said holder, and a substantially horizontal supporting flange above 75 said opening having one or more openings for attaching screws or bolts adapted to be secured in substantially vertical position in the lower edge of an instrument board.

10. A construction of the character described comprising a reel casing having an opening in its lower front portion with a 80 seat adjacent thereto, a flange member extending forwardly from said casing above and in advance of said seat for securing said casing to the lower edge of an instrument board, and a holder normally held in said 85 seat below said flange member.

CHARLES H. CUNO.
